CHARCOAL PACKAGE

James E. Foote, Westport, Conn., assignor to Diamond National Corporation, a corporation of Delaware

Filed Oct. 25, 1957, Ser. No. 692,442

3 Claims. (Cl. 44—40)

The present invention relates to a charcoal package and more particularly to a charcoal package made of a readily combustible paper product container in which the product is shaped to be readily molded by known molding procedures and wherein the package has superior burning qualities to those heretofore known.

In recent years there has come into widespread use the practice of families cooking their dinners over outdoor fires. Generally speaking, a fire in which the major element is charcoal in one of its forms is made in a stationary or portable grill. The meat and vegetables to be cooked are then placed on the grill and are thus flavored with the charcoal smoke, as well as being cooked by the heat from the charcoal.

At first the common procedure for obtaining a charcoal fire was to purchase charcoal briquettes in bulk and to attempt to ignite a bed of the charcoals with kindling made from paper or the like. Later, there came into widespread use a liquid igniting material for the charcoal which could be sprayed onto the charcoal from the container, and then the charcoal bed lit by a match applied to the igniting liquid. It was soon discovered that this arrangement had its deficiency, as it required the person making the fire to remove the charcoal from its bulk package and place a portion of that package in the grill. This, of course, was often a very messy job, so that it was difficult to make the fire without soiling the hands, and oftentimes also the clothes.

The above problems were solved to a large extent by the introduction of a self-contained package in which charcoal was sealed in a dust-tight manner. The package was made of a combustible material, preferably molded pulp, and was readily ignitable by the ordinary match. The charcoal was then lit by the burning molded pulp, so that no separate ignition material was necessary, nor was it necessary to handle the charcoal separately, as it could be handled completely by merely picking up the burnable package in which it was disposed, the package being dustproof as has been mentioned above.

The package referred to comprises a tray in which the charcoal was deposited, the tray having downwardly tapering side walls and a central upwardly tapering chimney. The tray was provided at its bottom with indentations leading from the outside into the chimney, so as to provide sufficient air for combustion. A cover was placed on the tray and adhered thereto by glue; this cover was generally planular, except for indentations adjacent to the exterior margin and adjacent the hole with which the central chimney of the tray communicated. The prior art package was ignited by applying a match to the package at the base of the chimney, so that the chimney began burning first and thereafter the rest of the package was consumed by the flames. With the prior art device, complete ignition of a substantial portion of the charcoal took place in approximately twenty minutes, this being substantially less than that obtainable with the material available before the introduction thereof.

2

Notwithstanding the advantages achieved by the prior art charcoal package, there were nevertheless certain features of it which could be improved, and it is to these features and characteristics that the present invention is directed.

It is therefore an object of the present invention to provide a package of burnable material containing charcoal in which a relatively greater amount of burnable material is disposed at the bottom of the package.

Another object is to provide a package of charcoal in a burnable container in which more rapid combustion of the charcoal will take place without the addition of any other ignition material.

It is a further object of the present invention to provide a package of charcoal which will cause the charcoal to stay piled in a pyramidal form rather than to fall apart and spread out, thus to obtain a more rapid ignition and hotter fire.

Yet another object of the present invention is to provide a charcoal package having a chimney therethrough in which the chimney is so shaped that as the material thereof burns away, the charcoal will fall into the chimney space, to thus take advantage of the greater heat which is extant in that space.

Still another object of the present invention is the provision of a charcoal package in which charcoal will be fed automatically into the part of the burning assemblage which is the hottest, whereby to promote the ignition of the charcoal.

Other objects and the nature and advantages of the instant invention will be apparent from the following description taken in conjunction with the accompanying drawings, wherein:

Fig. 1 is a perspective view looking toward the bottom of an improved package in accordance with the invention;

Fig. 2 is a cross-sectional view taken on the line 2—2 of Fig. 1;

Fig. 3 is a plan view of the bottom of the device;

Fig. 4 is a cross-sectional view taken on the line 4—4 of Figs. 1 and 3; and

Fig. 5 is a plan view of the top of the package.

Referring now to the drawings, there is shown in Fig. 1 a package 10 made of two parts; a first part 11 is in the shape, generally, of an inverted tray, and the bottom part 12 is in the shape of a cover for the tray. As best seen in Fig. 2, the upper part 11 has upwardly tapering exterior side walls 13 and a central downwardly tapering chimney 14 with an inturned bottom flange 14'. Both chimney 14 and walls 13 are joined by a flat top 15. The upper part 11 is preferably a unitary piece of molded pulp, it being noted that the shape of the upper part 11 is relatively simple and therefore one which may be molded with relative ease from a pulp slurry. Those skilled in the art of pulp molding will appreciate that it is a comparatively simple task to make a mold for the shape of the part 11, and also to separate the part 11 from its mold once it has been made.

As may be seen from Figures 1, 2 and 4, it is the lower part 12 which contains some of the more complex structure which is necessary to achieve the desired results. Thus, it may be seen from Fig. 1 that the bottom part 12 has four downwardly extending pads 17, 18, 19 and 20, each of which has a concave recess therein. The part 12 also has a central hole or aperture 21 having a flange 22 therearound for engagement with the bottom part of the chimney 14 and adjacent the flange 22 a lighting edge 23. A flange 24 adjacent the exterior margin of part 12 cooperates with the exterior side walls 13 of the part 11, in the manner best shown in Fig. 2.

As will be apparent, the pads 17, 18, 19 and 20 are to provide a passage through which air may flow from a

region exteriorly of the package 10 into the lower part of the chimney 14 and they are shaped in the manner shown to aid in feeding charcoal to the chimney space.

Fig. 3 is a plan view of the bottom of the package 10, showing how the four pads 17, 18, 19 and 20 cooperate to provide air passages leading to the chimney 14.

Fig. 4 is a view on a slightly enlarged scale showing how the concavity of two of the pads, pad 19 and pad 20, cooperate with the charcoal and the chimney 14 to feed charcoal into the chimney space.

The simple construction of the part 11 is seen also in Fig. 5, which also serves to emphasize the ease with which part 11 may be molded.

When the package of the present invention is to be used, it is ignited by applying a match to edge 23 at the base of the chimney 14. The molded pulp of the chimney 14 will begin to burn first, and at the same time there will be a conflagration of the part 12 as the fire proceeds along it from the base of the chimney 14. Thereafter, the fire will reach the exterior side walls 14 and consume them along with the top 15. The charcoal which is adjacent the lower part of the chimney 14 will be the first to be ignited; thereafter, as the chimney 14 burns away, the charcoal in the package adjacent thereto will have no support and will tend to fall or slide into the chimney space, aided by the shape of pads 17, 18, 19 and 20. Since this space is the hottest part of the entire package, this has the advantageous result of feeding more fuel into the hottest part of the fire. This, of course, aids in the rapid combustion of the entire amount of charcoal in the package.

In addition to the above feature, it will be understood that because the largest base of the package, i.e., the part 12, is at the bottom of the package during burning, and since there is comparatively greater amount of charcoal adjacent to this part 12, that charcoal will become ignited rather quickly and serve, in turn, to rapidly ignite the charcoal above it. Also, it may be seen that the upwardly tapering walls 13 will prevent to a large degree the charcoal from spreading out over a greater area than is taken up by the part 12, thus further tending to concentrate the fire and causing the entire amount of charcoal to become ignited quickly.

As has been noted above, the upper part 11 of the present invention is of such configuration that it may

be readily molded by known pulp molding procedures. In addition, however, it is to be observed that the lower part 12 also is such as to lend no difficulty to the usual pulp molding procedures and, in addition, is not subject to the warpage which has sometimes plagued those skilled in the art when making an item of molded pulp which is generally flat. It will be understood that once the part 13 is molded, it is treated as a tray and is filled with charcoal in known manner. Thereafter, the part 12 is handled as a cover and is secured to the part 13 by a suitable adhesive material. In use, of course, the bottom part 12 serves the function of a tray, i.e., it supports from below, and the upper part 11 acts as retaining walls and cover.

It will be obvious to those skilled in the art that various changes may be made without departing from the spirit of the invention and therefore the invention is not limited to what is shown in the drawings and described in the specification but only as indicated in the appended claims.

What is claimed is:

1. A dustproof rapidly burnable package of charcoal in a paper product container, wherein there are provided a spaced bottom and top, exterior walls and a central chimney, the bottom walls, top and chimney defining a charcoal-containing closed space about the chimney, the improvements comprising; the chimney tapering downwardly and being relatively wider at the top and relatively narrower at the bottom, the base being relatively larger than the top, and said exterior walls tapering upwardly from said relatively larger base to said relatively smaller top, whereby a large amount of paper product kindling material is at the bottom and the charcoal will feed inwardly to the chimney space when the chimney burns away.

2. The package of claim 1, wherein the top, chimney and exterior walls are integral.

3. The package of claim 1, said bottom having air passages therein communicating the base of the chimney with the atmosphere exteriorly of said package.
